W. I. ECKERT.

BRAKE BEAM FOR RAILWAY CARS.
APPLICATION FILED APR. 16, 1909.

927,645.

Patented July 13, 1909.

UNITED STATES PATENT OFFICE.

WILLIAM ISAAC ECKERT, OF SOUTH BETHLEHEM, PENNSYLVANIA

BRAKE-BEAM FOR RAILWAY-CARS.

No. 927,645.

Specification of Letters Patent.

Patented July 13, 1909.

Application filed April 16, 1909. Serial No. 490,240.

To all whom it may concern:

Be it known that I, WILLIAM ISAAC ECKERT, a citizen of the United States, residing at South Bethlehem, county of Northampton, State of Pennsylvania, have invented new and useful Improvements in Brake-Bearings for Railway-Cars, of which the following is a specification.

My invention is an improvement in brake beams for railway cars. Such beams are shown in U.S. patent of Lamont 782,971, of February 21, 1905, made of two sections with bolts securing the sections at top and bottom.

Another form of brake beam is shown in the patent of Crone 784,839, of Mar. 14, 1905, in which the fulcrum block, as it is sometimes termed, is made of one piece, the bar of which the fulcrum is made being bent back upon itself. My invention belongs to this general type of fulcrum block but is designed to provide a two-piece form with a detachable locking connection at the lower end requiring no bolts.

In the accompanying drawing, Figure 1 is a general view of my improved device. Fig. 2 is a view with parts detached, and Fig. 3 shows the parts partially detached.

In the drawing, 1, is a portion of the usual body beam, and 2, 3, represent the parts of my improved fulcrum which is of the usual construction except as to the connection between the two sections at the lower part. It is desirable to have the parts capable of separation, as in the patent of Lamont, rather than in one piece as in the patent of Crone, but my experience has been that it is also of advantage to dispense with the bolt for connecting the parts together, and

I have therefore substituted for the bolt a simple locking connection brought into effective use when the parts are brought together. The lower end of each part is provided with an inward extension *a*, which has a downward extension *b*, upon one edge, and a part *c* extending inwardly and terminating in an upward extension *d*. These parts are reversely arranged on the sections 2, 3, and it is only necessary in order to cause the parts to interlock to bring the lower ends of the sections at right angles to each other so that the extension *b* on the part 2 shall enter the space between the projection *d* and

the face of the depending part *a* of 3. In this position the part 2 is given a quarter turn, bringing the parts in locking engagement, after which a bolt 5 is passed through the usual openings 6, in the upper parts of the sections, preventing any detachment of the locking connections at the bottom of the sections.

The advantages of my invention, while apparent, are exceedingly important. The parts are interchangeable so that if one should break only that half requires to be replaced, a very important consideration. Further, if the fulcrum should break a new fulcrum could be at once adjusted without rendering necessary the taking off of the brake-shoe or removing the rivets from the brake-shoes, as is necessary with the devices in use at present. Another advantage of the construction is that not only is there no necessity for a bolt or rivet connecting the lower parts together, but no filler or washer is necessary in my improved construction.

What I claim is:

1. A fulcrum block for brake beams composed of two parts, the lower ends of said parts having interlocking connections, and means for holding the parts in their normal relation, substantially as described.

2. A fulcrum block for brake-beams composed of two interchangeable parts, said parts having locking connection at one end and a bolt holding the opposite ends together, substantially as described.

3. A fulcrum block for brake beams composed of two interchangeable parts, each part having a lower inward extension *a*, and an interlocking connection, substantially as described.

4. A fulcrum block for brake beams composed of two parts, each part having an inward extension *a* at its lower end, a downward extension *b*, a part *c* and an upward extension *d*; these parts being reversely arranged and interlocking, substantially as described.

In testimony whereof I have signed my name to this specification in the presence of two subscribing witnesses.

WILLIAM ISAAC ECKERT.

Witnesses:

CHARLES P. H. STINEMAN,

GEO. L. BAUM.
